UNITED STATES PATENT OFFICE.

MICHAEL B. GREEN, OF MEMPHIS, TENNESSEE.

COMPRESSION-BOX FOR OIL-PRESSES.

1,347,455.

Specification of Letters Patent. Patented July 20, 1920.

Application filed October 17, 1919. Serial No. 331,342.

To all whom it may concern:

Be it known that I, MICHAEL B. GREEN, a citizen of the United States, residing at Memphis, in the county of Shelby and State 5 of Tennessee, have invented certain new and useful Improvements in Compression-Boxes for Oil-Presses, of which the following is a specification.

This invention has reference to compression boxes for use in connection with the pressing of oil from cotton seed and other oil producing commodities, and its object is to provide a substitute for the older type of perforated plates, whereby a greatly increased output of oil with respect to quantity and speed is obtained, great strength of construction is obtained, and there is increased durability whereby there is a marked saving in renewals.

20 In accordance with the invention, provision is made for the ready escape of the oil forced out by pressure, the arrangement being such that while the aggregate area of the escape passages is large, such passages are 25 of individually small size so that the press cloth inclosing the seed meal or other material to be treated, is not distorted or torn and is consequently of long life, this being a particularly valuable feature since the cost of 30 press cloth has, in late years, been steadily increasing.

The extraction of the oil is accomplished in presses each made up of a column of compression boxes interposed with press cloth, 35 customarily of horsehair, lodged between the boxes and inclosing the meal, and the whole press is then subjected to sufficiently high pressure to cause the oil to flow out from the meal and find ready escape through the 40 boxes, which will, though provided with numerous passages, have such passages so disposed that the strength of the boxes will resist the heavy pressure, and the meal is retained without material restriction to the 45 free flow of the oil.

The invention lies in the formation and relation of the escape passages which are of relatively minute area where engaging the press cloth containing the seed, but are so 50 disposed that the compression box is nowhere sufficiently weakened to permit warping or distortion.

The invention will be best understood from a consideration of the following detailed description, taken in connection with 55 the accompanying drawing forming part of

this specification, with the understanding, however, that the invention is not confined to any strict conformity with the showing in the drawings but may be changed or modified so long as such changes and modification mark no material departure from the salient features of the invention as expressed in the appended claims.

In the drawings,

60 Figure 1 is an elevation of a press embodying the invention;

Fig. 2 is a plan view of a portion of one of the compression boxes;

Fig. 3 is an edge view of the structure in 70 Fig. 2 as seen from the left hand end;

Fig. 4 is a side view of one of the intermediate bars showing the connecting rods or rivets in cross section;

Fig. 5 is a section of the line 5—5 of 75 Fig. 2;

Fig. 6 is a section on the line 6—6 of Fig 4;

Figs. 7, 8, 9 and 10 show a series of cross sections of the bars illustrating progressive 80 steps in the formation of the bars.

Referring to the drawings, and especially to Fig. 1, there is shown a known form of press including a head or crown 1, a base 2, guiding pillars or posts 3, a series of plates 4, each with guiding angle bars 5, and compression boxes 6 to be supported on the plates 4 and guided by the angles 5. The material to be treated is as is customary, inclosed in suitable press cloth, and lodged on 90 the boxes 6 for compression between these boxes and plates 4. This is the usual procedure and requires no special description. The oil forced from the seed meal, or other commodity being treated, overflows the compression boxes and may be caught in a pan 8 and conducted to a suitable point of disposal.

The compression box 6 is, because of manufacturing reasons, formed of a series of longitudinal bars 6^a, shown as of rectangular cross section with longitudinal recesses or grooves 9 on opposite sides, except that bars 6^a forming the long side bars of the box have grooves 9^a closed at the ends, as shown in Fig. 3, instead of being as long as 95 the bars, as shown in Fig. 4, this preventing the marginal bars of the compression box from overflowing at the extremities.

The grooves 9 are, or may be, of semi-circular cross section so that when the bars are 110 brought together in face to face relation, the compression box is provided with a longi-

tudinal series of substantially circular passages extending throughout the length of the box. The upper edges of the grooves 9 are slightly rounded as shown at 10, thus 5 forming an inset portion of the groove or passage approaching the top of the box.

The bars 6^a are held in face to face relation by rivets or rods 11 which may be headed or otherwise shaped at the ends to clamp 10 the series of bars into a substantially continuous plate. Under the high compression used there is some passage of oil from the surface of the plate through the joints between the bars to the passages 9 and this is 15 facilitated by the rounded edges 10, reducing the joints adjacent to the top surface of the plate or compression box.

Cut into the grooves 9 from the top surface of each bar 6^a and diagonally traversing the overhang of the corresponding groove 9, is a slit 12, entering into the body of the bar toward the opposite side thereof at the surface to a greater extent than where entering the groove 9. This increases the length of the slot to a material extent where receiving oil from the meal being pressed, and the oil finds free escape into the corresponding groove 9, while such groove may be made narrow to avoid clogging by the material being pressed. The slits 12 are displaced longitudinally of the bars on opposite edges thereof so as to be in 20 staggered relation, this contributing to the strength of the bar. Furthermore, the body 25 of the bar immediately below each slit 12 is entered transversely by a bore or recess 13 enlarging the discharge end of the slit and therefore giving greater freedom of escape of the oil. Furthermore, the meeting edges 30 of the bars intermediate of the slits 12 have preferably matching and relatively minute notches 14 therein, adding still more to the area of escape of the expressed oil without noticeable diminution of the strength of 35 the bars.

The material, when prepared for the expressing of the oil or other liquid contents, is reduced to a condition of meal, and such meal has heretofore given trouble by finding 40 its way into and clogging the drainage passages, and the fibers of the press cloth in which the meal is confined also have found their way into the drainage passages, clogging them and causing the rapid wear of 45 the fabric. By the invention these objectionable features are overcome, since the drainage passages may be made finer than has heretofore been the case. Finer passages necessarily mean restricted drainage 50 area, but, by the disposition of the passages and their greatly increased number, the effective combined area of the passages is made larger than the combined area of drainage passages as heretofore constructed. 55 The resistance of the fine passages to the

flow of the oil or other liquid is reduced by the undercut recesses 13 and the lateral elongation of the slits 12, such elongation being greater than the lateral depth of the grooves 9. The notches 14 also add to the 60 area of drainage. The arrangement of the recesses, slits and notches is such that ample integral material of the bars remains in position to impart the necessary resistance of the bars to the high pressure to which meal, 65 from which the oil is expressed, is subject.

The passages for the escape of the expressed material progressively increase in size from the top surface of the bars to the grooves 9, so that despite the minute size 70 of each individual slit, resistance of such slit to the flow of the expressed material is greatly reduced and freedom of flow is obtained without liability of clogging or of 75 injuring the press cloth in which the meal is confined.

The invention provides an increased percentage of oil per ton of seed treated, causes a prolongation in the life of the press cloth, and a more free discharge of oil from 80 the cake into the main reservoir than has heretofore been the case.

What is claimed is:

1. A bar for the construction of compression boxes for oil presses, having grooves in 85 the side faces to form escape passages, with the top of the bar overhanging the grooves, and said overhanging portions having lateral slits extending from the top surface of the bar into the grooves, with the inner ends 90 of the slits slanting toward the opposite side of the bar and the slits staggered on opposite sides of the bar, each slit being underridden by a recess entering the body of the bar back of the groove and expanding into 95 said groove.

2. A bar for the construction of compression boxes for oil presses, having grooves in the side faces to form escape passages, with the top of the bar overhanging the 100 grooves, and said overhanging portions having lateral slits extending from the top surface of the bar into the grooves, with the inner ends of the slits carried toward the opposite side of the bar and the slits staggered 105 on opposite sides of the bar, each slit being underridden by a recess entering the body of the bar back of the groove and expanding into the said groove, the outer ends of the overhangs having relatively minute up and down notches intermediate of the entering 110 ends of the slits.

3. A bar for the construction of compression boxes for oil presses, having longitudinal grooves in the side faces to form escape passages with the top of the bar overhanging the longitudinal grooves, said overhanging portions having laterally extended recesses entering the bar in intersecting relation to the longitudinal grooves and said 115

overhanging portions having slits extending from the top surface of the bar to the longitudinal grooves through the overhangs with each slit intermediate of a recess and 5 the slits extending to the rear walls of the longitudinal grooves.

4. A bar for the construction of compression boxes for oil presses, having longitudinal grooves in opposite side faces to 10 form escape passages for the oil, with the top of the bar overhanging the grooves, said overhanging portions having entering slits extending laterally into the bar and into the grooves in intersecting relation thereto 15 to a greater depth than the portions of the grooves intersected by the slits, and said overhanging portions also having recesses formed therein to enlarge the slits where entering the grooves to the full depth of the 20 recesses, with each recess extending on opposite sides of the respective slit.

5. A bar constituting a longitudinal side bar in the construction of compression boxes for oil presses, having grooves in the side faces to form escape passages with the 25 grooved part of the outer face of the bar closed at the ends and the groove on the inner face of the bar open at the ends and with the top of the bar overhanging the grooves, said overhanging portions having 30 lateral slits extending from the top surface of the bar into the grooves with each groove entered by a plurality of said slits, and lateral recesses formed in the under surfaces of the overhangs with each recess extending 35 on opposite sides of a corresponding slit in communication therewith throughout the length of the recess, whereby to provide enlarged drainage area between a slit and the groove into which it empties. 40

In testimony whereof I affix my signature.
MICHAEL B. GREEN.
